BURNER POT

Bruce Hayter, Santa Fe, N. Mex., assignor to Oil Devices, Santa Fe, N. Mex., a limited partnership of Illinois

Application April 8, 1944, Serial No. 530,117

11 Claims. (Cl. 158—91)

1

My invention relates to an improvement in pot type burners and has for one purpose to provide improved means for delivering air to a liquid hydrocarbon burner.

Another purpose is to provide improved means for supplying secondary air to the mixture of vaporized hydrocarbon and primary air, in a hydroxylating, pot type burner.

Another purpose is to obtain silent combustion. Other purposes will appear from time to time in the course of the specification and claims.

My invention is illustrated more or less diagrammatically in the accompanying drawing, wherein:

Figure 1 is a vertical axial section of an embodiment of my invention;

Figure 2 is a similar partial section on an enlarged scale; and

Figure 3 is a similar partial section through a variation.

Like parts are indicated by like characters throughout the specification and drawing.

Referring to the drawing, 1 generally indicates an outer housing having a plurality of feet 2 between which are air inflow spaces 3. The housing is partly closed by a horizontal partition 4 centrally apertured as at 5. 6 is an angle ring which receives the upper outwardly extending flange 8 of the burner pot 7. 9 indicates an upper portion of the housing 1, which serves as a combustion chamber, or a heat radiating member. Any suitable draft means, not herein shown, may be provided for disposing of the heated gases and by-products of combustion. The pot 7 includes a shoulder portion 30 which is shown as lying in a plane generally perpendicular to the axis of the pot. The shoulder portion terminates in a cylindrical pot portion 31, preferably coaxial with the axis of the lower pot portion 7. The cylindrical portion 31 terminates in the flange 8.

One end of the pot is partially closed by a centrally apertured flame ring 10. The pot is shown as having a slightly concave bottom or closed end 11 which is continuous with and closest the end of the generally cylindrical side wall 12, the minimum diameter part of the pot which is provided with a plurality of primary air inlet apertures 13, circumferentially spaced about the wall portion 12 and located at various distances above the pot bottom. Located above, or beyond the lowest of the primary air inlet apertures 13 is a centrally apertured pilot baffle ring 14 supported on any suitable pins or supports 15. A liquid fuel is supplied to the pot along the pipe 16, the rate of flow being controlled by any

suitable control means generally indicated as 17. I illustrate, for example, a known type of float valve assembly with a manual control knob 18 for controlling the flow of fuel along the pipe 16. 5 However, it will be understood that any suitable control means, manual or automatic, may be provided for varying the rate of flow of liquid fuel along the pipe 16 or for maintaining a uniform rate of flow, when a uniform rate is desired. It will be understood that whereas I have shown a vertically axised pot, the pot may be horizontally axised or the axis may be variously inclined in relation to the vertical.

It will be understood that in pot type burners of the present type, a liquid hydrocarbon is vaporized by the heat of combustion taking place in or above the pot. The liquid hydrocarbon is admitted to the interior of the pot and is initially partially vaporized by the heat of hydroxylation taking place in the pot. As the liquid hydrocarbon is vaporized in the pot, it rises and is surrounded by a film of secondary air. The radiant heat from this combustion supplies the remainder of the additional heat necessary 20 to vaporize all of the liquid hydrocarbon. There is a differentiation in action between the so-called primary air and the so-called secondary air admitted to the interior of the pot. With reference to the present structure, the air entering through 25 the primary apertures 13 has a different action than the air entering through the secondary apertures 24 which are located in the circumferential pot wall portion 31. All of the oxygen in the air entering through the primary apertures 30 35 13 is fully consumed in the process of hydroxylation. The oxygen in the air entering through the secondary apertures 24 is only partially consumed, but all of the vaporized hydrocarbons 40 surrounded by the secondary air are entirely consumed.

When fuel is being supplied to the pot for a high fire, combustion takes place at a level defined by the area of inflow of the secondary air through the apertures 24. The flame flows 45 through the central aperture of the flame ring 10 and into the combustion chamber 9.

The present structure provides a particularly efficient means for supplying the secondary air and for maintaining a silent and efficient combustion. I employ for example the single row of secondary air inlets 24 which are made to direct jets of air upwardly and inwardly toward the axis of the pot, by the employment of additional apertures 33 in the wall portion 30, which direct 50 55 impinging jets of air, against the jets passing

through the apertures 32. The final composite jet or direction of flow, caused by the impinging jets from the apertures 32 and 33, is indicated at 34 in Fig. 2.

In the form of Fig. 3, I employ a lower pot 1a, with an outward or lateral enlargement having walls 30a and 31a. In the wall 31a I provide a row of secondary air inlet apertures 32a, shown as having axes inclined toward the open end of the pot. In the wall 30a I provide a row of inlet apertures 33a. The wall 30a is inclined and the axes of the apertures 33a are shown as perpendicular to the wall 30a. The result is a projection of jets of air toward the apertures 32a.

It will be understood that, in connection with the forms of Figs. 2 and 3, the inlets 32 and 32a may have, at choice, axes perpendicular to the axis of the pot or inclined toward the open end of the pot. An advantage of the form of Fig. 3 is that tilting the axes of the apertures 33a is unnecessary, since the wall 30a may be given its final form by a downward thrust against the upper edge of the pot, or by any suitable forming step. Both forms have this advantage: that the convergence between two sets of jets of inflowing secondary air takes place very close to the inner face of the pot.

It will be realized that whereas I have described and shown a practical and operative device, nevertheless many changes may be made in the size, shape, number and disposition of parts without departing from the spirit of my invention. I therefore wish my drawing and description to be taken as in a broad sense illustrative or diagrammatic, rather than as a limitation to my precise showing.

The use and operation of the invention are as follows:

In pot type liquid hydrocarbon burners it is highly important to provide an adequate supply of secondary air to a primary mixture in such a fashion that combustion noises are substantially prevented. It is important that the secondary air be provided in such quantities and at such location that the final mixture will burn steadily clear back to the wall of the pot, or to some other fixed plane or surface near the point of admission of the secondary air supply. In the present structure the secondary air is supplied in impinging jets which engage at a short distance inwardly from the wall of the pot and which provide an ample supply of secondary air at the point of admission. In practice in all the forms shown herein, there is provided quiet and efficient combustion, with an ample supply of air at the base of the jet. The impingement of the two inclined currents of air holds down the speed of flow of the jets and prevents any tendency for the jets to burn away from the inner face of the pot.

A primary cause of noisy combustion is the tendency of the base of the flame to leave the immediate vicinity of the orifice through which the air enters. By providing impinging jets I control or limit the speed of the air jet flow, and at the same time insure an ample supply of secondary air at the base of the flame, adjacent the inner face of the pot wall.

I claim:

1. In a burner pot for pot type burners, a pot member having a circumferential side wall and a closed end wall, the opposite end of the pot being open, the side wall having a plurality of primary air inlet apertures circumferentially spaced thereabout, said pot having an outward offset adjacent its open end, including a generally

cylindrical end wall portion and an intermediate wall portion connecting said cylindrical end wall portion with the side wall of the pot, each said wall portion having a plurality of secondary air inlet apertures, the axes of corresponding apertures of said two wall portions converging inside the pot.

2. In a burner pot for pot type burners, a pot member having a circumferential side wall and a closed end wall, the opposite end of the pot being open, the side wall having a plurality of primary air inlet apertures circumferentially spaced thereabout, said pot having an outward offset adjacent its open end, including a generally cylindrical end wall portion and an intermediate wall portion connecting said cylindrical end wall portion with the side wall of the pot, each said wall portion having a plurality of secondary air inlet apertures, the axes of corresponding apertures of said two wall portions converging and the axes of the apertures in the intermediate wall portion being outwardly inclined toward the apertures in the end portion.

3. In a burner pot for pot type burners, a pot member having a circumferential side wall and a closed end wall, the opposite end of the pot being open, the side wall having a plurality of primary air inlet apertures circumferentially spaced thereabout, said pot having an outward offset adjacent its open end, including a generally cylindrical end wall portion and an intermediate wall portion connecting said cylindrical end wall portion with the side wall of the pot, each said wall portion having a plurality of secondary air inlet apertures, the axes of corresponding apertures of said two wall portions converging, the axes of the apertures in the intermediate wall portion being outwardly inclined toward the apertures in the end wall portion and the axes of the apertures in the end wall portion being inclined toward the open end of the pot.

4. In a burner pot for pot type burners, a pot member having a generally cylindrical circumferential side wall provided with a plurality of primary air inlet apertures, and a closed end wall, the opposite end of the pot being open, the side wall having an outwardly extending portion terminating in a generally cylindrical end portion, the side wall of the pot having secondary air inlet apertures in the outwardly extending portion and in the cylindrical end portion, formed and adapted to direct converging jets into the pot.

5. In a burner pot for pot type burners, a pot member having a generally cylindrical circumferential side wall provided with a plurality of primary air inlet apertures, and a closed end wall, the opposite end of the pot being open, the side wall having an outwardly extending portion terminating in a generally cylindrical portion at the open end of the pot, the side wall of the pot having secondary air inlet apertures in the outwardly extending portion and in the cylindrical end portion, the axes of the apertures in the said two portions intersecting inside the pot.

6. In a burner pot for pot type burners, a pot member having a generally cylindrical circumferential side wall provided with a plurality of primary air inlet apertures, and a closed end wall, the opposite end of the pot being open, the side wall having an outwardly extending portion terminating in a generally cylindrical portion at the open end of the pot, the side wall of the pot having secondary air inlet apertures in the outwardly extending portion and in the cylindrical end portion, the axes of the apertures in the said

two portions intersecting closely adjacent the inner face of said cylindrical end portion.

7. In a burner pot for pot type burners, a pot member having a generally cylindrical circumferential side wall provided with a plurality of primary air inlet apertures, and a closed end wall, the opposite end of the pot being open, the side wall having an outwardly extending portion terminating in a generally cylindrical portion at the open end of the pot, the side wall of the pot having secondary air inlet apertures in the outwardly extending portion and in the cylindrical end portion, said outwardly extending portion being inclined outwardly and away from the open end of the pot.

8. In a burner pot for pot type burners, a pot member having a generally cylindrical circumferential side wall provided with a plurality of primary air inlet apertures, and a closed end wall, the opposite end of the pot being open, the side wall having an outwardly extending portion terminating in a generally cylindrical portion at the open end of the pot, the side wall of the pot having secondary air inlet apertures in the outwardly extending portion and in the cylindrical end portion, said outwardly extending portion being inclined outwardly and away from the open end of the pot, the axes of the secondary air inlet apertures in said outwardly extending portion being generally perpendicular to said outwardly extending portion, and converging with the axes of the air inlets in the cylindrical end portion closely adjacent the inner face of said cylindrical end portion.

9. In a burner pot for pot type burners, a pot member having a circumferential generally cylindrical side wall and a closed end wall, the opposite end of the pot being open, the side wall including two generally cylindrical portions of different diameter and a connecting wall portion therebetween, the cylindrical portion of maximum diameter being located adjacent the open end of the pot and having therein a plurality of circumferentially spaced secondary air inlet apertures, the cylindrical portion of smaller diameter having therein a plurality of primary air inlet apertures spaced circumferentially thereabout, and said connecting wall portion having therein additional secondary air inlet apertures adapted to deliver impinging jets of air toward the jets delivered inwardly through said first mentioned secondary air inlet apertures.

10. In a burner pot for pot type burners, a pot member having a circumferential generally cylindrical side wall and a closed end wall, the op-

posite end of the pot being open, the side wall including two generally cylindrical portions of different diameter and a connecting wall portion therebetween, the cylindrical portion of maximum diameter being located adjacent the open end of the pot and having therein a plurality of circumferentially spaced secondary air inlet apertures, the cylindrical portion of smaller diameter having therein a plurality of primary air inlet apertures spaced circumferentially thereabout, and said connecting wall portion having therein additional secondary air inlet apertures adapted to deliver impinging jets of air outwardly toward the jets delivered inwardly through said first mentioned secondary air inlet apertures.

11. In a burner pot for pot type burners, a pot member having a circumferential generally cylindrical side wall and a closed end wall, the opposite end of the pot being open, the side wall including two generally cylindrical portions of different diameter and a connecting wall portion therebetween, the cylindrical portion of maximum diameter being located adjacent the open end of the pot and having therein a plurality of circumferentially spaced secondary air inlet apertures, the cylindrical portion of smaller diameter having therein a plurality of primary air inlet apertures spaced circumferentially thereabout, and said connecting wall portion having therein additional secondary air inlet apertures adapted to deliver impinging jets of air outwardly toward the jets delivered inwardly through said first mentioned secondary air inlet apertures, said connecting wall portion being upwardly and inwardly inclined toward the open end of the pot.
